UNITED STATES PATENT OFFICE

101,082

DESIGN FOR A FOUNTAIN BRUSH

John A. Kranley, Brooklyn, N. Y.

Application May 21, 1936, Serial No. 62,761

Term of patent 3½ years

To all whom it may concern:

Be it known that I, John A. Kranley, a citizen of the United States, residing at Brooklyn, in the county of Kings and State of New York, have invented a new, original, and ornamental Design for a Fountain Brush, of which the following is a specification, reference being had to the accompanying drawing, forming part thereof.

I claim:

The ornamental design for a fountain brush as shown.

JOHN A. KRALNEY.
